SIGNAL TRANSMISSION METHOD AND APPARATUS

Austin G. Cooley, Rutherford, N. J., assignor to
Wide World Photos, Inc., New York, N. Y., a
corporation of New York

Application October 1, 1936, Serial No. 103,506

21 Claims. (Cl. 179—2)

This invention relates to transmission systems and more particularly to systems of transmission employing telephone facilities as the transmission medium or as a connecting link in a transmission system.

An object of the invention is to provide a system of transmission of graphical representations, pictures, etc., whereby the usual telephone service line may be employed as a connecting link between a transmitter and a receiver, but without the necessity of effecting physical connection to the line wires proper.

Various methods of coupling a picture signal transmitter or a picture signal receiver to a telephone line have been proposed heretofore. Thus in one type of system the picture signals are translated into acoustic waves which are acoustically impressed upon the usual telephone transmitter. One of the serious objections to the acoustic method is the unavoidable distortion that is introduced in the signal transmission. I have found that it is possible to employ the usual telephone service wire or wires for such transmission as electro-optical transmission, without introducing any appreciable distortion and without making any physical connection to the line wires proper. In carrying out this object of the invention, the picture or electro-optical signals are impressed on the telephone line preferably by electro-magnetic induction through the intermediary of the ear-piece or receiver of the usual telephone subscriber's set.

A feature of the invention relates to a novel form of coupling member whereby electric signals may be applied to a telephone line by electro-magnetic induction through the ear-piece or receiver of a telephone set.

Another feature relates to a novel coupling for applying signals to a telephone line through the usual ear-piece or receiver, the coupling means being provided with adjusting means whereby satisfactory coupling efficiency to the line may be attained on various types of telephone receivers, but without actual or physical connection to the line.

A further feature relates to a novel coupling arrangement whereby the usual telephone service receiver can be used simultaneously as a receiver of distantly generated signals, and as a transmitter for locally generated signals.

A further feature relates to the method of employing existing telephone subscriber's equipment for picture or electro-optical transmission, without physical connection to the telephone wires

and without disturbing the normal functioning of the telephone plant or equipment. As a result of this feature, it is possible to employ any telephone earpiece or receiver as a transmitter link for the purpose of electro-optical transmission, thus saving time required to install apparatus usually employed for that purpose.

A still further feature relates to the novel organization, arrangement and relative location of parts which go to make up an improved electro-optical transmission system, and an improved device for coupling electro-optical apparatus to a telephone line without physical connection thereto.

Other features and advantages not specifically enumerated will become apparent after a consideration of the following detailed descriptions and the appended claims. In the drawing,

Fig. 1 is a composite schematic circuit diagram of an electro-optical system embodying features of the present invention.

Fig. 2 is a view partly in section, of an improved coupling device according to the invention.

Fig. 3 is a detailed view of part of the structure shown in Fig. 2.

Fig. 4 is a view of a modification of the device of Fig. 2.

Fig. 5 is a schematic diagram showing a modification of part of the system shown in Fig. 1.

Referring to Fig. 1 there is shown in generalized schematic form a typical signal transmission system to which the invention may be applied. While the drawing shows, merely for explanatory purposes, the invention as embodied in an electro-optical transmission system, it will be understood that it is equally well applicable to similar systems of transmission, e. g., facsimile, printing telegraph, and in fact to any system where signals representing intelligence to be communicated are to be applied to a telephone line without physical connection thereto. In Fig. 1 the numeral 1 represents schematically any well-known form of electro-optical transmitter whereby the light values of a representation to be transmitted are translated into corresponding electric currents. Preferably the device 1 is of such a type that the signals are translated into a correspondingly modulated carrier wave or other wave having an inherent frequency component which is directly and positively related to the speed of the electro-optical scanning or analyzing mechanism.

For a detailed description of such a device reference may be had to Patent No. 2,045,294, issued to Austin G. Cooley on June 23, 1936.

The output of the device 1 consisting preferably of an audio frequency signal-modulated carrier wave, may be applied to a terminal amplifier tube represented schematically by the numeral 2, although it will be understood that the tube 2 may be the last or output stage of the amplifier usually incorporated as part of the device 1. The output circuit of tube 2 is represented schematically as including the primary winding 3 of a suitable output coupling transformer, although any other well-known form of coupling may be employed. The secondary winding 4 of the output transformer is preferably connected through a polarizing battery 5 to the movable arms of a double-pole double-throw reversing switch. The fixed contacts of switch 5 are connected to the coils 7, 8 of an electro-magnetic coupling device 9.

As shown more clearly in Fig. 2 this coupling device comprises a U-shaped laminated iron core 10 on each leg of which is mounted one of the coils 7, 8. The coupling device 9 is arranged to be mounted in predetermined spaced relation to the diaphragm 11 of any common type ear-piece 20 or receiver, such for example as the receiver of the usual telephone subscriber's set. For this purpose the coupling magnet may be fastened in any suitable manner to the cross-bar 12 and suitable projections or pins 13 may be provided on the core to engage a non-magnetic washer 14 so as to prevent the ends of the core from touching the diaphragm 11. As shown in Fig. 2 the coupling device is designed for use with one well-known form of telephone receiver the latter comprising an enclosing casing 15 of hard rubber or similar material having suitably fastened on its interior the magnet 16 carrying at its upper ends the coils 17, 18. The diaphragm 11 is clamped in place between the peripheral edge of the casing 15 and the annular rim 19 of the cap or mouth-piece 20, the latter being threaded on to the casing 15 in the well-known manner. As shown clearly in Fig. 2 the ends of core 10 project through the circular opening in the cap 20 into proximity with the coils 17 and 18. Preferably, although not necessarily, the core 10 is designed so that the spacing between the poles and the diaphragm is about the same as the spacing between the poles of the receiver magnet and diaphragm.

The bar 12 carrying the coupling device may be held in place on the cap 20 in any suitable manner, preferably however it is held in place by a substantially closed cap 21 of rubber or other non-magnetic and sound-deadening material, this cap 21 being provided with a flexible rim 22 which is capable of being stretched to fit over the rim of the cap 20. The coupling device is thus held firmly in place without the necessity of employing screws or other similar fastening means, and the coupling device can be readily removed for adjustment or repair, without affecting the telephone receiver in any way. If desired the cap 21 may be provided with suitable binding posts 23 to which the lead wires to the coils 7, 8 are connected. If desired also a compressible washer 24 may be inserted between the bar 12 and the rim of cap 20 as shown.

In order that the telephone receiver may be used simultaneously for the purpose of impressing the locally generated signals on the telephone line and also for its usual purpose of translating distantly generated signals or for monitoring the locally generated signals, the rubber cap 21 is provided with an outlet 25 into which is tightly

fitted the end 26 of a suitable listening tube. While any known form of listening tube or other arrangement may be employed, it is preferred to employ a tube constructed similar to a stethoscope having a pair of branched tubes 27, 28 with suitable ear-pieces at their ends (not shown). We have found that with this arrangement, it is possible for the coupling device to be acting for purposes of transmission at the same time that one is listening in through the tubes 27, 28 to the character of the transmission so as to detect any irregularities thereon, i. e., for monitoring or to listen-in on signals transmitted back from the receiving station. It will be understood that the use of the listening tube is not necessary, and if desired the listening-in may be effected directly through the opening 25. As an alternative, the cap 21 may be provided with a series of perforations for listening-in purposes. When the signals are being transmitted in the form of a modulated audio-frequency carrier wave it is preferable to design the acoustic chamber defined by members 20, 21, 25, 26, 27 and 28, or a part thereof, so that the acoustic carrier frequency component is suppressed at the ear-pieces of tubes 27, 28. This may be achieved by proportioning the length, internal diameter and frictional resistance of the inner surface of tubes 27, 28 so as to absorb or attenuate the carrier frequency to the desired extent. Inasmuch as the method of proportioning the characteristics of the tubes 27, 28 for this purpose, is well-known in the acoustic filtering art further description thereof is not deemed necessary herein. This acoustic chamber may also be employed as a load, or damping factor, on the vibrations of the diaphragm. Instead of achieving the acoustic carrier frequency suppression by proportioning the dimensions and other characteristics of the tubes 27, 28, if desired the bar 12 may be replaced or supplemented by one or more perforated baffles or diaphragms to introduce sufficient attenuation in the carrier frequency acoustic wave before it reaches the ear-pieces at the ends of tubes 27, 28. Consequently one may listen through the ear-pieces at the ends of tubes 27, 28 without undue interference from the picture signals that are being impressed on the telephone line. Thus the ear-pieces may be used to monitor the outgoing signals or they may be used to listen-in on signals that originate at the opposite end of the telephone line.

While Fig. 1 of the drawing shows the coupling arrangement applied to one particular form of telephone line coupling, it will be understood that this is merely representative. Thus the modulated carrier wave which is impressed upon the coils 7, 8, is repeated by electro-magnetic induction through the coupling device described, to the subscriber's loop comprising the repeating coil 30, 31, the condenser 34, and the switch-hook contacts. A similar arrangement may be employed at the receiving end of the telephone line. Thus the modulated carrier wave is received in the conventional manner by the telephone receiver 36 which carries a coupling device 37 similar to the device 9. The received waves are transferred by electro-magnetic induction to the conductors 38, 39 to the picture synthesizing or reproducing device represented schematically by the numeral 41, which may be of any well-known type such for example as illustrated in Patent No. 2,045,294.

I have found that in order to achieve the optimum coupling efficiency between the device 9 and the telephone line it is necessary to polarize

the core 10 in a predetermined relation to the normal polarization of the magnet 16. For this purpose preferably the output circuit of the tube 2 is connected to the adjustable battery 5 through the reversing switch 6 so that the normal polarity of the coupling core may be varied to effect optimum coupling. It will be understood of course that any well-known method may be employed to synchronize the transmitting picture analyzer with the reproducing synthesizer, and preferably, although not necessarily, the carrier frequency itself may be used for synchronizing as described in said Patent No. 2,045,294. It will be understood also that the invention is not necessarily limited to a system wherein the received picture signals are transferred to the reproducer 41 through the receiver 36, and it will be obvious to those familiar with the art that the received signals may be transferred from the telephone line 32, 35 to the device 41 in any well-known manner.

Instead of employing a separate polarizing battery such as the battery 5 for polarizing the coupling device, the usual plate supply source or battery of the output tube 2 may be employed for this purpose. Thus as shown in Fig. 5 the output or plate circuit of tube 2 including the usual plate supply source 43, is connected to the coupling coils 7, 8 through the reversing switch 6.

In certain cases, it may be desirable to adjust the spacing between the core 10 and the diaphragm 14. While the arrangement shown in Fig. 2 enables the coupling core to be rotated around the vertical axis of the receiver merely by turning the cap 21, and while the spacing between the core 10 and magnet 16 may to a certain extent be varied by employing washers 24 of different thicknesses, it may be desirable to provide independent spacing adjustment. Thus as shown in Fig. 4 the cap may be formed in two parts 44 and 45 the former being of a rigid non-magnetic material, while the latter is preferably of a flexible non-magnetic material, the two parts being either joined together as a unit or separable from each other. In the latter case the part 45 should have sufficient resiliency to firmly grip the part 44 against the rim 20 of the receiver cap. The bar 12 carrying the coupling core and coils is provided with two adjusting screws 46, 47 by means of which the spacing between the core 10 and the magnet 16 may be accurately adjusted. Instead of fastening the adjusting screws 46, 47 to the bar 12 as shown, a spring or rubber washer (not shown) may be interposed between the bar and the rim 48 of the receiver cap, this spring or washer normally tending to impel the coupling unit upwardly against the ends of the adjusting screws 46, 47. Likewise, if desired, a spring or rubber washer may be interposed between the stop disc 14 and the magnet coils. With this arrangement, therefore, it is possible to orientate the core 10 with respect to the magnet coils 17, 18; to polarize electrically the coils 7, 8; and to adjust the spacing between the core 10 and the coils 7 and 8 or magnet 16 for optimum results.

While certain preferred embodiments have been disclosed herein it will be understood that various changes and modifications may be made therein without departing from the spirit and scope of the invention. For example while the drawing shows the coupling as applied to a service receiver of the type forming part of a desk-set type telephone, it will be understood that the invention may be readily applied to service re-

ceivers of the so-called French or hand-phone type, and that corresponding changes in dimensions of the parts can be readily made to accommodate them to the latter type of receiver.

What is claimed is:

1. In a signaling system, the combination of a line, a device at one end of said line normally designed only to transmit signals to the line and another device at said end of the line normally designed only to receive signals from the line, said other device including an electromagnet, and electromagnetic induction means positioned adjacent said electromagnet and energized by signal currents in the form of an audio frequency modulated carrier to be transmitted to the line for applying said signals to the line through said electromagnetic means.

2. In a signaling system, the combination of a telephone line, a telephone service transmitter at one end of said line designed normally only to transmit signals to the line, an electromagnetic telephone service receiver at said end of the line normally designed only to receive signals from said line, electromagnetic induction means positioned adjacent said receiver and energized by signal currents to be transmitted for applying said signal currents to said line through said receiver for transmission to a distant station.

3. In a signaling system, the combination of a telephone line terminating in a subscriber's loop including a telephone service transmitter designed normally only to transmit signals to the line and a service telephone receiver having an ear-piece designed normally only to receive signals from said line, a source of signals local to said loop and to be transmitted over said telephone line, and electromagnetic means for applying said signals to said line by induction through said receiver for transmission to a distant station.

4. In a signaling system, the combination of a telephone line terminating in a subscriber's loop, a service telephone receiver for said loop normally designed only to receive signals from the line and to reproduce them acoustically, said receiver including an ear-piece with a magnetizing coil, a source of other signals local to said loop to be transmitted over said line, and an electromagnetic induction device adjacent said coil for coupling said source to said line through the coil in said receiver for transmitting said other signals over said line to a distant station.

5. In a signaling system the combination of a telephone line terminating in a subscriber's loop, a telephone receiver for said loop having an ear-piece with a diaphragm for reproducing signals received from said line, a device local to said loop for generating picture signals in the form of a modulated carrier wave, an electromagnet having a core positioned adjacent to but in spaced relation to said diaphragm, and means for energizing said electromagnet under control of said picture signals for transmitting said picture signals to a distant station.

6. In a signaling system, the combination of a telephone line terminating in a subscriber's loop, a service telephone receiver for said loop having an ear-piece normally designed only to receive signals from said line to reproduce said signals acoustically, said receiver having a magnet therein, means local to said loop for generating signals in the form of a modulated carrier wave, and electromagnetic means for applying said wave to said line by electromagnetic induction through the magnet in said receiver.

7. In a signaling system, the combination of a telephone line terminating in a subscriber's loop, a service telephone receiver for said loop having an ear-piece with a diaphragm and designed normally only to reproduce acoustically signals received from said line, a source of other signal currents local to said loop, a space induction device energized by signals from said other source, means to mount said device in spaced relation to said diaphragm, whereby said other signals are transmitted to said line by electromagnetic coupling to said ear-piece, and means to limit the proximity of said device to said diaphragm.

8. In a signaling system, the combination of a telephone line terminating in a subscriber's loop, a service telephone receiver for said loop and normally designed only to receive electric signals from the line and for reproducing said signals acoustically, an electromagnet mounted in spaced relation to the diaphragm of said receiver, means to pass a steady polarizing current through said electromagnet and means to apply a signal modulated carrier wave to said electromagnet for transmission to a distant station over said telephone line.

9. In a signaling system, the combination of a telephone line terminating at each end in a subscriber's loop, each loop having associated therewith a telephone service transmitter and a telephone service receiver, the transmitter being designed normally only to transmit signals to the line and the receiver being designed normally only to receive signals from the line and to reproduce them acoustically, a picture signal transmitter, a picture signal receiver, and means to couple said receiver and transmitter to said line without physical connection thereto, the last-mentioned means including an electromagnet mounted adjacent the ear-piece of the service receiver at one of the subscriber's loops for transmitting signals from the picture signal transmitter to the line electromagnetically through said service receiver.

10. In combination, a telephone service receiver normally designed only to receive telephone signals from the associated telephone line, said receiver having a magnet and diaphragm enclosed by an ear-piece, means to removably mount an electromagnet on said ear-piece in spaced relation to said diaphragm while allowing sound waves generated by said diaphragm to pass through said means, said electromagnet being arranged for energization by signals to be transmitted to the telephone line by electromagnetic induction from said electromagnet to said receiver magnet.

11. In a device of the character described, the combination of a pair of electromagnets, a sound reproducing diaphragm mounted between said electromagnets in spaced relation thereto, one of said electromagnets being designed normally for energization by incoming signal currents to reproduce said currents acoustically, the other of said electromagnets being designed for energization by outgoing currents for impressing said outgoing currents on said line electromagnetically through the first electromagnet.

12. In combination a device of the character described comprising a diaphragm and a cooperating electromagnet normally designed to be energized by sound currents received from a distant station, and another electromagnet mounted in spaced relation to the diaphragm and on the opposite side of the diaphragm from the first electromagnet, and means to energize said

other electromagnet by locally generated picture signal currents to induce picture currents into the first electromagnet for transmission to a distant station.

13. In combination, a telephone service receiver, having an ear-piece with an electromagnet and diaphragm, a removable cap for said ear-piece, said cap enclosing another electromagnet for transmitting signals electromagnetically to the first-mentioned electromagnet, said cap having sound channels open to the air and in communication with the diaphragm of the receiver, whereby the receiver may be used as an acoustic reproducer and as an electromagnetic coupling device for transmitting signals to the telephone line by electromagnetic induction.

14. In combination, a telephone service receiver having an ear-piece and an electromagnet energized by received telephone currents to produce audible signals, a cover for said ear-piece and forming therewith an acoustic chamber, another electromagnet mounted within said chamber in inductive relation to the first electromagnet, said cover having an opening for the emergence of sound waves.

15. The combination according to claim 14 in which said chamber, together with said opening, are designed to act as an acoustic filter.

16. In combination a telephone service receiver having an ear-piece, a cover for said ear-piece, a listening tube coupled with said cover and forming therewith an acoustic filter, said filter being designed to suppress acoustic waves of an undesired frequency, and an electric coupling device mounted between said cover and said ear-piece.

17. In combination, a telephone line, a telephone subscriber's sub-station set connected to said line, said sub-station set having a service telephone receiver including a magnet energized by received telephone currents, means to transmit signals to the said telephone line through said receiver including an electromagnet energized by the signal currents to be transmitted, and means to polarize said electromagnet by a steady polarizing current.

18. In combination, a telephone line having a telephone subscriber's sub-set including a service telephone receiver with a pair of magnetic poles, an electromagnet mounted in inductive relation with said poles, a signal generator, means to pass a steady polarizing current through said electromagnet and to energize said magnet in accordance with the signals from said signal generator whereby said signals are impressed on the telephone line for transmission thereover.

19. In combination according to claim 18, in which the means to polarize said electromagnet includes a polarizing battery and a reversing switch which is connected between the signal generator and the said electromagnet.

20. In a signaling system, means to couple a signal generator to a telephone line comprising a service telephone receiver having a magnet and sound reproducing diaphragm, an electromagnet mounted in spaced relation to said diaphragm and adapted to be energized by signal currents to be transmitted to the line by electromagnetic induction from said electromagnet to the magnet in the receiver and thence to the telephone line, a housing for said electromagnet and forming with said receiver an acoustic chamber having sound outlets whereby said receiver may be used as an acoustic reproducer at the same time that

it is being used to couple the transmitted signals to the telephone line.

21. In a device of the character described, an audio frequency device, and a telephone system including telephone receivers; means to connect said audio frequency device to said telephone

system which includes a pair of magnets in circuit with said device, polepieces for said magnets shaped to fit the opening in a receiver cap, and means for securing the first mentioned means to a telephone receiver.

AUSTIN G. COOLEY.
